United States Patent Office

Des. 184,590
Patented Mar. 10, 1959

184,590

TOY VEHICLE

Voorhis Frederick Wigal, Jackson, Tenn., assignor to Thomas M. Johnson, Decatur, Ga.

Application January 2, 1958, Serial No. 49,109

Term of patent 14 years

(Cl. D34—15)

FIG. 1

Des. 184,590

PAGE 2

FIG. 2

FIG. 3

FIG. 4

Fig. 1 is a side elevational view of the toy vehicle embodying my new design.

Fig. 2 is a top plan view thereof.

Fig. 3 is a front elevational view of the toy vehicle shown in Fig. 1.

Fig. 4 is a rear elevational view thereof.

The side not shown is a mirror copy of the side shown in Fig. 1.

I claim:

The ornamental design for a toy vehicle, substantially as shown and described.
